UNITED STATES PATENT OFFICE.

SAMUEL H. WATKINS, OF LINN FLAT, TEXAS.

MOTOR.

SPECIFICATION forming part of Letters Patent No. 287,893, dated November 6, 1883.

Application filed September 12, 1883. (No model.)

To all whom it may concern:

Be it known that I, SAMUEL H. WATKINS, a citizen of the United States, residing at Linn Flat, in the county of Nacogdoches and State of Texas, have invented a new and useful Motor, of which the following is a specification, reference being had to the accompanying drawings.

This invention relates to motors, and is especially adapted to operate a churn-dasher. Its object is to provide a motor possessing superior advantages in point of simplicity, inexpensiveness, easy operation, and general efficiency.

15 In the drawings, Figure 1 is a perspective view of my improved motor. Fig. 2 is a vertical transverse sectional view of the same.

Referring to the drawings, A designates the end base-pieces of the frame, from each of which extends a pair of uprights, B B, connected by longitudinal top beams, C C, that have bearings D D for a transverse operating-shaft, E, carrying a fly or balance wheel, F, between beams C C, a crank-disk, G, at one end, 25 and an operating-crank, H, or a band-wheel at its other end.

Between the uprights B B, at one side of the frame and near the bottom thereof, are secured a longitudinal beam, I, and another beam, J, above this, the latter beam, J, being provided with a perforation, K, through which passes the screw-threaded lower end of a guide-bar, L, which has its end secured by nuts M N, respectively above and below beam J, 30 while its top end is retained in a hole or recess, O, in the under side of the beam B, as shown. By removing the nuts the guide-bar can be readily separated from the frame.

P is a socket-piece, which is formed with a 40 lateral arm, Q, sliding on bar L, a top tongue, R, and a bottom recess, S, into which works a set-screw, T. To the tongue R is pivoted the lower end of a pitman, U, connected with the crank-disk, and the dasher V is secured in the 45 recess S by the set-screw T.

The beam I is provided with a segmental recess, W, that receives the churn-body, (shown in dotted lines,) and at one side of this recess is hinged an elastic curved fastening-wire, X, adapted to have the eye Y at its free end sprung into engagement with a pin, Z, at the other side of the recess W.

The operation and advantages of my invention will be readily understood. It is very simple, and its parts are readily separable for 55 substitution or repair.

I claim as my invention—

1. The combination of the frame comprising the uprights, longitudinal top beams, beam I, having means for fastening the churn, and beam J, the guide-rod secured perpendicularly between the top beam and beam J, the main shaft having the crank-disk, the socket-piece comprising the arm sliding on the rod, the tongue, and bottom recess, means for fastening the dasher in said recess, and the pitman pivoted to said tongue and connected to the crank-disk, substantially as and for the purpose set forth.

2. The combination of the frame of the motor, comprising the uprights, the top beams, C C, one of which has the recess O, and the beam J, having the perforation K, the guide-rod fitted in recess O and perforation K, and secured by the nuts M and N above and below 75 beam J, the socket-piece comprising the lateral arm sliding on the rod, the tongue, and the bottom recess having the set-screw, the main crank-shaft, and the pitman connected therewith and pivoted to the tongue, substantially as and for the purpose set forth.

In testimony that I claim the foregoing as my own I have hereto affixed my signature in presence of two witnesses.

SAMUEL H. WATKINS.
